UNITED STATES PATENT OFFICE.

MAURICE MAYOROWITZ, OF NEW YORK, N. Y.

DETACHABLE-HEEL CONSTRUCTION.

Application filed May 1, 1926. Serial No. 106,147.

This invention relates to improvements in detachable heel constructions.

An object of the invention is to provide a new and improved detachable heel arranged to permit a dealer in boots and shoes to readily provide a boot or shoe with a leather heel or with a rubber heel or a heel of other material according to the desires of the customer.

Another object is to enable the user of a boot or shoe to readily replace a worn-out heel by a new one.

A further object is to securely hold the detachable heel in place and to prevent moisture, dust or other extraneous matter from passing into the joint formed between the detachable heel and its support.

In order to accomplish the desired result, use is made of a plate attached to a lift secured to the sole of the boot or shoe, the plate being provided with longitudinally extending bayonet slots, a detachable heel provided with headed studs engaging the said bayonet slots, and removable fastening means extending through the sole, the sole lift and plate and engaging the said detachable heel. Use is also made of springs struck up on the plate and surrounding the terminals of the said bayonet slots to be engaged by the heads of the said studs to draw the detachable heel firmly against the sole lift.

A practical embodiment of the invention is represented in the accompanying drawings forming a part of this specification, in which similar characters of reference indicate corresponding parts in all the views.

Figure 1 is a perspective view, showing a pair of shoes on the feet of the user equipped with my improvements;

Figure 2 is a perspective view, showing the heel lift removed from the sole plate;

Figure 3 is a view in longitudinal section, showing my improved heel lift in operative position;

Figure 4 is a view in transverse section, on the line 4—4 of Figure 3;

Figure 5 is a view in transverse section on the line 5—5 of Figure 3;

Figure 6 is a fragmentary view in section, showing my improved coupling means disassociated;

Figure 7 is a plan or face view of the sole plate before it is secured to the heel;

Figure 8 is a fragmentary view in front elevation of the heel, showing the lap elevated;

Figure 9 is a plan view of a modified form of seat for a locking pin;

Figure 10 is a view in section on the line 10—10 of Figure 9;

Figure 11 is a plan view of a modified form of heel lift;

Figure 12 is a view in section, on the line 12—12 of Figure 11;

Figure 13 is a fragmentary view in section, illustrating a modification;

Figure 14 is a view in longitudinal section, similar to Figure 10 but illustrating another modification.

1 represents the heel of a shoe or slipper, 70 which may be of any suitable material and which is provided at its lower end with a spacer 2 that may be secured to the heel in any approved manner and may constitute a single piece or several pieces and be of any 75 suitable material, in accordance with the desire of the trade.

3 represents my improved removable heel lift, and my invention resides in the means for connecting the lift and the heel, or, more 80 specifically, the lift and the spacer which constitutes a fixed part of the heel.

Referring more particularly to Figures 1, 2, 3, 4, 5, 6, 7 and 8, 4 represents a sole plate, 85 which is of metal of suitable thickness and of the desired resiliency and strength for the work to be performed.

This plate 4 conforms in shape to the lower end of the heel and is secured to the heel by nails 5 driven through openings 6 in 90 the plate 4 and into the heel. The plate is further secured in place by means of an integral extension 7 located at the front edge of the plate and adapted to be bent at substantially right angles to the plate along the 95 dotted line 8 in Figure 7.

At the free end of this extension 7 spurs 9 are provided which are bent at right angles to the extension and are forced into the front of the heel, as indicated at 10 in Figure 3. 100 This extension 7 is provided with a nail receiving opening 50 and with a larger opening 11 for a purpose which will more fully hereinafter appear.

The extension 7 is completely covered by 105 a lap 12 which is secured to the front face of the heel in any approved manner, but I preferably employ an adhesive in addition to other securing means, which will be hereinafter explained.

The sole plate 4 is provided with a plurality of spring seats 13 with bayonet slots 14

communicating therewith. The smaller ends of the bayonet slots 14 are located at the center of the seats 13 with the larger ends of the slots in the flat or main portion of the sole plate. I may employ any desired number of these spring seats, but I have illustrated three which I find are ample for the purpose although I do not wish to be limited to any particular number.

19 These spring seats are formed by upwardly off-setting the metal of the plate 4, and are made with central depressions 15 therein. These spring seats 13 may be outlined throughout a portion of their circumference by a slot or slit 16, which gives the effect to the seats of independently upwardly movable spring tongue carrying seats. The exact form of these seats may vary as, for example, in Figures 9 and 10 I show a seat 17, corresponding to seat 13, which is integral with the plate 4; or, in other words, the slit or cut 16 is omitted.

20 In Figure 14 I illustrate an integral seat 18 which has no central depression, and this constitutes a modified form of my invention.

25 The plate 4 is also formed with a locking spring finger 19, which is stamped or cut from the central portion of the plate 4, extends transversely of the plate, and has a downward resilient tendency so that the normal position of the free end of this finger 19 is below the lower face of plate 4. The spring finger 19 has an opening 20 therein adjacent its free end and is formed 30 with an upwardly offset portion constituting a cam 51 located intermediate the ends of the spring finger, for a purpose hereinafter described.

35 The heel lift 3 will of course conform in general contour with the contour of the heel and may be made of any desired thickness and also of any suitable material. As a matter of fact, it is my intention to make these lifts of various materials, such as leather, rubber or a combination of material, so that the wearer can replace not only a worn lift but can also substitute any other type of lift desired.

40 Each lift is provided with headed studs 21, corresponding in number and relative location to the number and location of the spring seats 13. Another pin 22, which is without a head, is also carried by the lift 3 and is so located that when the parts are 45 in coupled relation this pin 22 will be in the opening 20 of spring finger 19. I may, of course, make this lift in various ways and do not wish to be confined to any particular manner of forming the same nor to the 50 specific means for supporting the pin.

45 In Figure 4, I illustrate the lift 3 as having a plate 23 embedded in the material of the lift and upwardly offset at suitable points, and to these upwardly offset parts 60 of the lift the pins may be riveted, as shown

at 24. Above the upwardly offset portions of the plates 23, the material of the lift is cut away or omitted, leaving recesses 25, and portions of this upper face of the lift may be cupped or recessed, as shown at 26 in Figure 6, so as to act as suction cups to grip the surface of the sole plate 4 and aid the coupling pins and seats in the perfect securing and holding of the parts in coupled relationship.

70 I would call particular attention to Figures 3 and 8 of the drawings, wherein it will be noted that I secure an eyelet, which is of course a rivet 27, in registering openings in the lap 12, and in the opening 11 of extension 7 a conical or tapering guide 28 constitutes a part of the eyelet 27 and is so located as to admit a pin or other instrument into position to engage the cam 51 of spring finger 19 to elevate the free end of the spring 80 finger, lifting it off of the pin 22 to allow the heel lift 3 to be removed.

85 In the modification illustrated in Figures 11 and 12, the lift 3 is provided with a plate 29, secured or embedded therein, and carrying the coupling pins, as shown. This plate 29 may have spurs 30 of a length to extend entirely through the lift and be upset at their lower ends, as shown at 31, or may be otherwise secured in place.

90 Figure 13 illustrates another form of device, showing a pin 21 which is projected through the lift 3 and has its lower end spread or expanded, as shown at 32, and this pin also has a fixed flange 35 adjacent its upper end which is embedded in the material of the lift. In this modification, the pin 21 is shown cooperating with a spring finger 33, corresponding to the spring finger 19 except that this finger 33 is shorter and 100 has an upturned end 34 against which the pin 21 bears to prevent retrograde movement of the heel lift to uncouple the same from the sole plate.

95 The operation of coupling or connecting the lift to the sole plate is as follows: The headed pins 21 are moved through the larger ends of the slots 14, with the pin 22 resting on the spring finger 19. While the lift is pressed tightly against the sole plate 115 4 it is given a sidewise or lateral movement, causing the heads of the pins 21 to ride over and onto the spring seats 13, thus drawing the spring seats downward against their inherent resiliency or tension, and when the 120 heads of the pins ride into the sockets or depressions 15 of the seats and the pin 22 rides into the opening 20 of spring finger 19 the parts will be securely held and accidental displacement absolutely prevented. 125 When the parts are in coupled or locked relationship, the lift is held not only by the spring tension of the spring seats 13 but there is a binding action between the surfaces of the plate 4 and the lift 3. This 130

may be augmented by the recesses 26, illustrated in Figure 6, which create a strong suction to further clamp the parts together. In any event, the parts are so rigidly coupled that they will sustain all possible strain to which a device of this kind is naturally subjected without causing the lift to be uncoupled or detached. The only way the lift can be uncoupled or detached is by the insertion of the pin through the eyelet 27 against the cam face 51 to lift the free end of the spring finger 19 out of coupled engagement with pin 22. The lift can then be moved laterally of the heel, drawing the headed pins out of the bayonet slots 14 until the pins are released.

A very desirable arrangement is to provide lugs or enlargements 36 in at least one wall of each of the keyhole slots 14 adjacent the smaller end of the slot so that a certain amount of resistance is offered to the movement of the shanks of the pins, and the pins are thereby held in the center of their seats with greater effectiveness.

While I have illustrated what I believe to be the preferred embodiments of my invention, it is obvious that various slight changes and alterations might be made in the general form of the parts described without departing from my invention, and the device may be employed for other uses, and hence I do not limit myself to the precise details set forth but consider myself at liberty to make such slight changes and alterations as fairly fall within the spirit and scope of the appended claims.

I claim:

1. A coupling, including a plate, a lift, movable spring seats cut from the plate, said movable seats being separated for a portion of their length from the plate and having bayonet slots extending transversely of the plate, pins projecting upwardly from the lift, and heads on the pins adapted to be moved into the larger openings of the slots and moved along the slots to the center of the seats when the lift is moved transversely relative to the heel whereby the seats are put under tension to hold the lift against the plate.

2. A detachable heel construction, including a sole plate adapted to be fixed to a heel, a lift, spring seats being detached for a portion of the length thereof from the sole plate and movable relative to the plate and having bayonet slots extending transversely of the plate, the narrower ends of said slots being concentric with the center of the seats, headed pins projecting upwardly from the lift, the heads on the pins being adapted to be moved into the larger openings of the slots and moved along the slots to the center of the seats when the lift is moved transversely relative to the heel whereby the seats are put under tension to hold the lift against

the plate, a headless pin carried by and projecting upwardly from the lift, and a spring finger having an opening receiving said headless pin to hold the lift against lateral movement.

3. A detachable heel construction including a sole plate adapted to be fixed to a heel, a lift, spring seats carried by the sole plate and movable relative to the plate and having bayonet slots extending transversely of the plate, said seats being detached from the plate for a portion of the length of the slot, pins projecting upwardly from the lift, heads on the pins adapted to be moved into the larger openings in the slots and along the slots, to the center of the seats when the lift is moved transversely relative to the heel whereby the seats are put under tension to hold the lift against the plate, lugs integrally formed with the seats adjacent the narrow ends of the slots, said lugs frictionally engaging the pins and tending to hold the pins in the narrow ends of the slots, and releasable means for holding the lift against lateral movement.

4. A detachable heel construction, including a sole plate adapted to be fixed to a heel, a lift, movable spring seats cut from the sole plate and having bayonet slots extending transversely of the plate, said seats being detached from the sole plate for a portion of the length of the slot, the narrower ends of said slots being concentric with the center of the seats, pins projecting upwardly from the lift, heads on the pins adapted to be moved into the larger openings of the slots and moved along the slots to the center of the seats when the lift is moved transversely relative to the heel whereby the seats are put under tension to hold the lift against the plate, a pin on the lift, and a spring finger on the plate adapted to engage said last-mentioned pin and hold the lift against lateral movement, a cam on the spring finger, and a guide in the heel for the admission of a tool to engage the cam and lift the finger out of locked engagement with the last-mentioned pin whereby the lift may be moved to its releasing position.

5. A detachable heel construction, including a sole plate adapted to be fixed to a heel, a lift, spring seats struck from the sole plate and having bayonet slots extending transversely of the plate, the narrower ends of said slots being concentric with the center of the seats, pins projecting upwardly from the lift, heads on the pins adapted to be moved into the larger openings of the slots and moved along the slots to the center of the seats when the lift is moved transversely relative to the heel whereby the seats are put under tension to hold the lift against the plate, an extension on the plate adapted to be fixedly

- secured to the heel, a lap fixed to the heel, and covering said extension, said extension and lap having registering openings therein, an eyelet in said opening, a guide carried by the eyelet, and a spring finger locking the lift against lateral movement and adapted to be engaged by an instrument projected through said guide to engage the finger and elevate it from its locking position. 45
6. A detachable heel construction including a sole plate adapted to be fixed to a heel, a vulcanizable heel lift, spring seats struck from the sole plate and having bayonet slots extending transversely of the plate, an anchoring plate imbedded in the material of the lift and having upwardly offset portions, pins carried by said upwardly offset portions of said anchoring plate and projecting upwardly from the lift, and heads on the pins cooperable with the bayonet slots, said lift having recesses in its upper face around the pins thereof and overlying the upwardly offset portions 50
- 25 of the anchoring plate whereby the weight is transmitted to the body of the heel and is not applied to the upwardly offset portions of the anchoring plate. 55
7. A detachable heel construction, including a sole plate adapted to be fixed to a heel, a lift, spring seats struck from the sole plate and having bayonet slots extending transversely of the plate, the narrower ends of said slots being concentric with the center of the seats, pins projecting upwardly from the lift, and heads on the pins adapted to be moved into the larger openings of the slots and moved along the slots to the center of the seats when the lift is 60 moved transversely relative to the heel. 65
8. A detachable heel construction including a sole plate adapted to be fixed to a heel, a vulcanizable heel lift, movable spring seats cut from the sole plate and having bayonet slots extending transversely of the plate, said seats being detached from the sole plate for a portion of the length of the bayonet slot, an anchoring plate imbedded in the material of the lift, pins carried by said anchoring plate and projecting upwardly from the lift, and heads on the pins cooperable with the bayonet slots. 70
9. A detachable heel construction including a sole plate having openings adapted to receive fastening devices to aid in securing it to the heel, said sole plate also having an extension projecting angularly from the sole plate and adapted to be disposed flush up against one face of the heel, said extension having spurs at its extremity 75 designed to be driven into the heel, a lift, and releasable means for securing the lift to the sole plate. 80
10. A detachable heel construction including a sole plate adapted to be fixed to a heel, a heel lift, said sole plate being provided with bayonet slots, the metal of the sole plate being cut adjacent an end of a slot to provide a movable seat, an anchoring plate carried by the lift, pins supported by the anchoring plate and projecting outwardly from the lift and heads on the pins co-operable with the seats for aiding in securing the length of the sole plate. 85

MAURICE MAYOROWITZ.
